CONSTRUCTION BLOCK

Alden B. Dow and Robert Goodall, Midland,
Mich.; said Goodall assignor to said Dow

Application November 21, 1935, Serial No. 50,847

4 Claims. (CL. 72—41)

This invention relates to improvements in construction blocks, and particularly to blocks adapted to be used in the construction of the walls of buildings. It has for its general object 5 the provision of a pre-cast masonry block where- with walls presenting the appearance of having unbroken vertical joints can be constructed in which the vertical joints between successive horizontal courses are broken.

Another object of the invention is to provide a 10 standard block wherewith single thickness walls having a very high resistance to lateral pressure can be constructed.

A further object of the invention is to provide 15 a block wherewith either straight or zigzag walls, and geometrically patterned walls, can be constructed.

To the accomplishment of the foregoing and 20 related ends the invention, then, consists of the means hereinafter fully described and particularly pointed out in the claims, the annexed drawing and following description setting forth in detail the block embodying the invention, such description constituting, however, but several of 25 various forms in which the principle of the invention may be utilized.

In said annexed drawing:

Figure 1 is a plan view of two of our blocks 30 showing them in the position which they occupy as normally used in a wall construction. Figures 2 and 3 are, respectively, a side elevation and an end elevation of one of the blocks shown in Figure 1.

Figure 4 is a plan view of our corner block. 35 Figures 5 and 6 are, respectively, a side elevation and a joint-face elevation of the corner block shown in Figure 4.

Figures 7 and 8 are isometric views of partially 40 constructed walls showing the relationship after assembly, between the straight block shown in Figures 1, 2, and 3, and the corner block shown in Figures 4, 5, and 6.

Our blocks are substantially hexahedral prisms 45 which are adapted to be embossed on the exposed faces thereof. In the drawing we have illustrated the exposed faces of all of our related blocks as provided with protuberant portions presenting a plane surface, said protuberances being beveled on all their edges at an angle of approximately 45° to the plane of the exposed side faces of the block; but we do not limit ourselves to this particular form of embossing, since any desired ornamentation may be employed without disadvantage.

All of our blocks are preferably provided with 50 voids which extend between the bases of the hexahedral prisms constituting the blocks. These voids may advantageously be made substantially triangular in shape and so placed in each block of the group that they will be in

vertical alignment when the blocks are laid in the horizontal courses, thereby to permit doweling and successive horizontal courses together if desired.

Our blocks are cast in permanent molds, and 5 may be made of concrete, cinder-base, clay, or other suitable materials. It is possible to incorporate pigments with the material from which the block is made, at the time of casting, to produce blocks colored in any desired manner. The 10 molds can be recessed to provide suitable embossing on the exposed faces of the blocks. The blocks can be laid up in successive horizontal courses with any suitable bonding agent, such as 15 hydraulic mortar, etc.

The straight block illustrated specifically in 20 Figures 1, 2, and 3 is in the shape of a right parallellipiped, whereof the perimeters of the bases are congruent oblique parallelograms which have supplementary angles of substantially 45° and 135°, and the ratio of the altitude of either base to the length of the longer side thereof is approximately 1 to 2. Thus, in Figure 1, the acute angles 41 and 42 of the parallelogram constituting the perimeter of one base of our straight block 25 are angles of approximately 45°. We have, however, found it advantageous in practice to modify the shape in plan section of the straight block slightly from that of a true parallelogram. Thus, as seen in elevation from the line 46 on the joint-face 45 of the block, the face is struck off toward the side face of the block at a very slight angle from the true diagonal. The opposite end face is also struck off at a corresponding angle toward the opposite side face. This provides a tapering 30 crevice 47 between adjacent blocks in a bed or horizontal course for holding the bonding agent. The width of the block between side faces 44 is proportioned to the length of the block between the oblique end faces in the ratio of 1 to 2, i. e. in 35 a block six inches in width the length of the block is approximately 12 inches.

As illustrated in plan, the straight block is 40 made with triangular shaped voids 43, which construction, although preferable, is not essential, 45 since the blocks may be made solid or have voids of other shapes. It will be noted that the voids in the straight blocks, and as well in all other blocks employed in our constructions, line up between successive beds, permitting the doweling 50 of blocks together with concrete and reinforcing bars to form lintels, columns, etc., where it is necessary to resist heavy strains. This feature permits great flexibility in spanning openings such as fireplaces, etc., and constructing ornamental grilles.

We preferably provide the respective side faces 44 of the straight block with raised portions beveled on all edges, e. g. 48 and 49, at an angle of about 45°. This gives a decorative appearance 55 60

to the side of walls constructed with such blocks and permits pointing up of the bonding agent between adjacent blocks. Other suitable ornamental effects may be employed on the side surfaces 5 faces 44, such as geometric pattern designs, imitation stone finishes, etc.

The straight block illustrated in Figures 1, 2, and 3 is used as a field block in straight walls. The straight blocks mitre to form the corners 10 in alternate horizontal courses; in the other courses two straight blocks combine with a corner block to form a corner. The straight blocks may also be used to obtain certain ornamental effects, such as pierced masonry grilles, niches, 15 etc.

The corner block illustrated in Figures 4, 5, and 6 is a substantially right triangular prism, whereof the perimeters of the bases are substantially right isosceles triangles. The edges 50a 20 and 51a of the faces 50 and 51 of said triangles, which include the right angle, correspond in length to the length of the sides 44 of the oblique parallelograms which form the bases of our straight block. The exposed faces 50 and 51 of 25 our corner block correspond exactly in size to the faces 44 of the straight block. The diagonal face 52 of the corner block is struck off toward each face 50 and 51 at a very slight angle, beginning at the lines 53 and 54, respectively, as were 30 the end faces of the straight block, to provide a more suitable crevice for the bonding agent between the adjacent blocks in a bed.

The corner block is used in alternate courses to bond corners. It is used in pairs to form square 35 piers and lintels, such lintels preferably being reinforced. It is also used in alternate courses in a zigzag wall.

Figures 7 and 8 show how the straight block, illustrated in Figures 1-3 inclusive, and the corner block, illustrated in Figures 4-6 inclusive, are employed in straight walls and in corners. The wall section shown in Figure 7 is adapted to be combined with the wall section shown in Figure 8, but for purposes of illustration is separated therefrom. In Figure 8 the lower horizontal course 45 is formed, reading from left to right, of two straight blocks, a corner block, two straight blocks, a corner block (not shown), and a straight block. The second horizontal course directly 50 thereabove is formed entirely of straight blocks, and this includes the two blocks in the lower course of Figure 7. The third successive horizontal course is again similar to that of the first, and consists, including the upper course of 55 Figure 7, reading from left to right, of two straight blocks, a corner block, two straight blocks, a corner block, and a straight block.

It will be noted that all vertical joints in any one horizontal course run parallel to each other, 60 and that all joints in the horizontal course immediately above and below the first course run at right angles to the joints in said first course and parallel to each other to form a broken vertical joint throughout the wall structure to effect a bond.

Other modes of applying the principle of our invention may be employed instead of those explained, change being made as regards the means employed, provided the means defined by the 65 following claims be used.

We distinctly point out and claim as our invention:

1. A wall structure having broken vertical joints comprising successive horizontal courses of blocks, the bases of said blocks being congruent, 5 oblique parallelograms which have supplementary angles of substantially 45° and 135° and a ratio between the altitude of either of said parallelograms to the length of the longer side thereof of approximately 1 to 2, said blocks being arranged in each course so that the acute angles of the bases of a block lie adjacent the obtuse angles of the bases of each of the adjacent blocks in the same horizontal course, said acute angles being also in superimposed relationship to the 15 obtuse angles of the bases of blocks in the course immediately therebelow, whereby the wall structure presents on each side the appearance of having unbroken vertical joints,

2. A wall structure having broken vertical joints comprising successive horizontal courses of blocks, the bases of said blocks being congruent, 20 oblique parallelograms which have supplementary angles of substantially 45° and 135° and a ratio between the altitude of either base of said parallelogram to the length of the longer side thereof of approximately 1 to 2 and the end faces of 25 said blocks are struck off at a relatively small angle from the approximate vertical center thereof towards the acute angles of said oblique parallelograms, said blocks being arranged in each course so that the acute angle of the bases of a block lie adjacent the obtuse angles of the bases of each of the adjoining blocks in the same 30 horizontal course, said acute angles being also in superimposed relationship to the obtuse angles of the bases of blocks in the course immediately therebelow, whereby the wall structure presents on each side the appearance of having unbroken vertical joints.

3. A building block substantially in the shape of a parallelepiped whereof the perimeters of all lateral sections parallel to the bases thereof form congruent oblique parallelograms which have obtuse angles of substantially 135°, and the ratio 45 of the altitude of said parallelograms to the length of the longer side thereof is approximately 1 to 2; the end faces of the block are struck off at a relatively small angle from approximately the vertical center thereof towards the acute 50 angles of said oblique parallelograms, and having a diagonal brace member extending substantially between the apexes of said obtuse angles.

4. A building block substantially in the shape of a parallelepiped whereof the perimeters of all lateral sections parallel to the bases thereof form congruent oblique parallelograms which have obtuse angles of substantially 135°, and the ratio of the altitude of said parallelograms to the length of the longer side thereof is approximately 55 1 to 2; the laterally exposed side faces of the block are provided with embossures chamfered on all edges; the end faces of the block are struck off at a relatively small angle from approximately the vertical center thereof towards the acute 60 angles of said oblique parallelograms, and having a diagonal brace member extending substantially between the apexes of said obtuse angles.
